MACHINE FOR TRANSFERRING BOTTLES
FROM A CARRIER SWINGABLE IN AN AR-
CUATE VERTICAL PATH TO A VERTICAL-
LY OSCILLATORY RECEPTACLE CARRY-
ING MEMBER

Soren Madsen, Bergenfield, and Joseph F. O'Brien, Englewood, N. J., and Claude D. Keith, Lake Mahopac, N. Y.; Irene M. Keith administratrix of said Claude D. Keith, deceased; said Madsen assignor to Irene M. Keith, as administratrix

Application May 28, 1943, Serial No. 488,932

5 Claims. (Cl. 226—14)

1

This invention relates to improvements in transfer machines for bottles and like articles.

This invention is adapted for use in bottling plants to transfer bottles in relatively large groups, such as case-loads, from one point or position to another and particularly to take bottles from a suitable bottle-feed line, transfer the load to a cellular or non-cellular bottle-carrying case and insert the bottles therein without the usual dropping of the bottles, or to remove empty bottles from such a case and to transfer the same to a suitable support such as a conveyor-belt for subsequent feeding to a washing machine or the like. Our invention, however, is not limited to the transfer of bottles alone, but may be used for the transfer of like articles having rim-beads or equivalent tops.

Objects of this invention are to provide a power-driven machine adapted to move a transfer-head, to a starting position in substantial parallelism with the tops of a group or load of articles, such as bottles, on a suitable initial support, to cause an automatic engagement at such starting position with the tops of such articles arranged in vertical position; to lift said head upwardly and to transfer the same from such initial or starting support to a delivery position over a suitable delivery support and to automatically release the load from said transfer head to deliver the same on said delivery support; to provide a machine that will lift and move the articles from an initial starting position to a delivery position while maintaining the said articles in substantially vertical position; to provide a bottle-transfer head movable as a whole in a vertical arc and preferably comprising a relatively stationary bottle-positioning and holding member having for each bottle a bottle-receiving opening cooperating with bottle-engaging plate reciprocable in a horizontal plane over said positioning member and having a registerable receiving opening provided with a communicating radial slot having edges adapted to securely and completely engage the neck of the bottle beneath the conventional outwardly-extending lip or rim-bead (which is slightly greater in diameter than the neck of the bottle), and upon movement in the opposite direction relatively to said holding and positioning member, to completely release said bottles, in combination with means for mechanically mov-

2

ing and shifting in opposite directions said reciprocable member of said transfer head into engaging and releasing positions at opposite terminals of movement of the machine; to respectively engage and release the bottles at such terminals of movement of the machine; to provide in such a machine a double-acting shifting mechanism operable at one terminal of movement of the transfer head to shift the reciprocable bottle-engaging member to engage the tops of the bottles and in an alternate movement, when the carrier reaches the opposite terminal of movement, to shift the same bottle-engaging member in the opposite direction to disconnect the transfer head from the load of bottles and to release and deposit the bottles on a suitable support; to provide, in a machine of the type specified, a bottle-spreading mechanism whereby a load of bottles will be received in contacting position from a conventional conveyor line, aggregated into a suitable load, at one end of the machine and then spread in order to separate the individual bottles from each other a suitable distance corresponding with the spacing requirements of a cellular case to be filled or with other transfer mechanism for subsequently handling such bottles; to utilize in a machine of the type specified a transfer head turning about a horizontal axis or shaft in an arcuate vertical plane and cooperating mechanism adapted to lift and transfer bottles from a point or position at one side of said horizontal shaft or axis and to release and deposit the load of bottles at the opposite side of said horizontal axis; to provide mechanism that jointly and in synchronism with such arcuate movement will move or tilt a cellular case for a short distance in a direction opposite to the arcuate movement of the bottles and back again to meet and intercept the bottles and during and prior to the end of their arcuate movement, and thus to position the mouths of the honey-comb cells or compartments in a plane in which the bottoms or heels of the bottles during the last part of their transfer movement will be engaged by the rear walls of the honey-comb chambers, thus causing said rear walls to function as guides to facilitate the entry of the bottles into the honey-combs or cells and causing the bottles readily to enter such mouths while the case will move with the head and bottles during the last

part of the arcuate movement thereof, thus avoiding necessity for accurately aligning the cases longitudinally or for the use of guide members and avoiding the usual dropping of the bottles; to mount a bottle transfer head on a drive shaft extending co-axially of the path of movement of the carrier and to oscillate said carrier in a substantially semi-circular path alternately to opposite sides of said drive shaft to engaging and releasing positions substantially level with each other and with said shaft; to provide an arcuate movable transfer head having a floating vertical movement relatively to its mounting means whereby when an obstruction is met the transfer head will move vertically to avoid rigidity of the arcuate movement and prevent breakage of bottles or of the mechanism; to provide a shifting mechanism operable by contact with the mounting shaft of the bottle transfer head to move the movable member of the transfer head into engaging and releasing positions.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Fig. 1 is a perspective view of a machine embodying my invention employed as a filling machine for cellular or honey-comb cases;

Fig. 1a is a perspective view partially broken away showing the operating mechanism for the bottle-engaging and releasing members and the bottle stops for bottle-spreading mechanism embodied in our said machine;

Fig. 11 is an enlarged fragmentary view in perspective of a portion of the transfer head and bottles in engaged position, parts being broken away 25 to illustrate the construction of the head;

Fig. 12 is a view in perspective of the bottle-spreader partially broken away to illustrate the construction thereof and operating elements therefor when the spreader is in closed and 30 locked position and the bottle-stop pins lowered out of operative position;

Fig. 12a is a fragmentary sectional view on the line 12a—12a of Fig. 12;

Fig. 13 is a fragmentary view similar to Fig. 35 12 showing the rear corner of the bottle-spreader in spread position with the bottle stops in operative position and also illustrating the lever and cam mechanism for actuating the spreader;

Fig. 13a is a fragmentary end elevation of the 40 40 lever and eccentric-pin mechanism shown at the bottom of Fig. 13;

Fig. 14 is a fragmentary view in perspective showing part of one section of the spreading device and the constructional features thereof;

Fig. 15 is another view in perspective showing the spreader and bottle stopping mechanism with the top members eliminated to show the operating levers therefor;

Fig. 16 is a side elevation partly broken away, 50 50 of a modified construction in which bottles are taken from a cellular case and deposited on a conveyor belt;

Fig. 17 is a top plan view of the corner of the transfer-head employed by me;

Fig. 17a is a bottom plan view of a portion of 55 said transfer head;

Fig. 18 is a fragmentary section on the line 19—19 of Fig. 17 with the parts in disengaging positions; and

Fig. 19 is a section similar to Fig. 18 showing the parts in bottle-engaging position.

Our invention, in its preferred form, embodies a suitable skeleton supporting frame 10 having at a suitable level and preferably at substantially the level of a suitable conventional bottle-feeding mechanism 11 a starting support 12 preferably including a longitudinally channelled article-receiving-and-spreading platform or shelf 12' adapted to receive a series or plurality of rows, comprising a load of articles, such as bottles from said feed mechanism. The bottles are when received spread transversely into said plurality or series of longitudinal rows by conventional feed mechanism, and are moved, while in substantial or actual abutment with each other, into the lon-

itudinal channels and the spreading platform 12' spreads these bottles longitudinally to position the same in accordance with the requirements of the receptacle or other element on which they are to be deposited, and also to permit a more facile engagement of the same by a transfer head, as hereinafter specified. The spreading platform 12' is preferably composed of a series of sections 12a disposed transversely of the path of feeding movement of the bottles, each section being adapted when the bottles are accumulated or aggregated on the spreading platform to support a transverse row of bottles comprising one bottle from each longitudinal line or row thereof and all such sections except one being movable to separate from another and to carry a row of bottles thereon to cause a longitudinal spreading of the series of rows of bottles. A conventional bottle-case carries twenty-four bottles and we preferably receive and spread an entire case-load at one time. With such a load our receiving and spreading platform is adapted to spread six rows longitudinally in relation to each other, it being understood that the individual bottles in a row are initially, in the feeding operation, separated or spread from each other transversely and are maintained in such transversely-spread condition by the use of channel side rails or partitions 12b on the sectional bottle-spreader. The frame of the machine also provides at substantially the same horizontal level as the spreading mechanism a delivery support 13. This delivery support may comprise, in whole or in part, a conveyor belt 13x which is adapted to feed boxes and preferably cellular or honey-comb cases 14 into a position in substantial registration linearly with the load of bottles on the receiving and bottle-spreading shelf or support 12'.

A vertically-movable bottle-transfer head 15 is mounted to oscillate from its starting and bottle-engaging position over and in parallelism with said bottle-spreader to a bottle-depositing position above a case or other suitable delivery support and we preferably mount said head on arms 16 fixed on an oscillating drive shaft 17 disposed transversely of and adjacent to rear end of the spreading shelf or bottle support and above the tray and box or case support. The arms 16 are movable vertically in the arc of a circle and the transfer head is thus, upon movement by such arms to starting or bottle-engaging position, adapted to move down over the tops of the articles and with bottles to engage such tops just below the rim-beads common to all beverage bottles. This engagement is accomplished by using the mounting frame or transfer head 15 and mounting thereon (Figs. 11, 17 to 19) a relatively stationary bottle-guiding-and-receiving member 15' having bottle receiving openings 15a of suitable dimension and a shiftable or reciprocable bottle-engaging member 15b provided with bottle-receiving openings comprising a receiving-portion 15c registerable with the opening 15a and a communicating fork-shaped bottle-engaging slot 15d contracted in relation to the receiving openings 15a and 15c and then shifting, through the operation of a suitably-timed actuating member 18 on the machine, of the said shiftable bottle-engaging member. Upon such swinging movement of the transfer head to starting position and engagement of the load, which usually comprises twenty-four bottles, said head is then swung or oscillated in a semi-circular vertical path by said head-mounting arms to the opposite side of the pivotal or axial shaft and the load is there de-

posited on a suitable support and preferably so deposited in a case or box supported at such other side of said pivotal shaft. The transfer head is guided so as to maintain a horizontal position during its swinging movement by a pair of articulating levers 19 pivoted at 19' on the members 10' at one end and at the opposite end to the frame member 30c. The transfer head is so mounted on a parallelogram of swinging or oscillating arms and so guided as to cause said head during its bottle-carrying vertical movement to be continuously maintained in horizontal position so that the bottles carried thereby will be held in substantially vertical position. The bottles are thus while held in vertical position moved or swung in an arcuate or semi-circular path from the spreading shelf or table to a support at the opposite side of the shaft or pivot, and we have found that a load of bottles may be released from carriers and set down on any suitable support at such opposite side without clatter or clash of any kind, and in some cases it will be desirable merely to move these bottles to a horizontal support such as a conveyor belt at such opposite sides of the machine and to release the bottles on such support after which they will be conveyed away before a new load is set down thereon by the transfer head. In one form of our invention, however, the bottoms of the bottles are preferably directly inserted into honey-comb chambers or cells of a conventional bottle-carrying wooden case. These cells are usually square or cubical in conformation and closely fit the bottles, and in the instant invention, in the transfer of bottles, after the same are lifted or moved to their highest vertical position they will move during the last half of their movement in a downward arcuate path. In order to insert bottoms of bottles so transferred or moving without in the mouths of the cellular compartments would require great accuracy of longitudinal positioning of the case and/or a complicated mechanism for guiding the honey-combs of the case and bottles into registration. We avoid any such complicated mechanism and enable the insertion of the bottoms of the bottles into the cellular cases by providing means for simultaneously rocking or shifting the box or case into transversely aligned position and for causing longitudinal alignment and also providing for a successive movement of the several rows of the load into the mouths of the several rows of cells in the case during movement of the load of bottles to releasing position. This successive insertion of the several rows is accomplished by providing means for tilting upwardly one end of the box or case into inclined position in relation to the bottoms of the bottles whereby the bottoms of the end row of bottles on the carrier will be engaged by rear partitions or walls of the cells while in inclined position and at an elevation considerably above the final horizontal support, whereupon the case is then permitted to move down or be lowered conjointly with the carrier and load of bottles but at a slower rate so that during such downward movement the several rows of bottles in the carrier will successively enter successive rows of cells or compartments. In this way each of the rows of bottles will be cleanly and efficiently deposited within their compartments without the necessity of any guides or other extraneous means and without any noise or clatter. The top edges of the box or case by this tilting movement cause the rear partitions of each cell to form a guide

which first engages the heel of the bottle and guides the same into its cell in the case and we have found that by this method the longitudinal alignment of the case or box may be merely approximate and that in case the case or box is materially out of proper position, the bottles will, after contact with the rear partitions of the end row move the case on its support to enable insertion of the bottles in its cells. This condition, however, causes some noise, while if the box is properly positioned no noise will occur.

In the case-filling embodiment of our bottle-transfer handling machine, the empty cases 14 (see Figs. 1, 3 and 4) are moved or fed by hand or by suitable mechanism now shown, into approximate position over a case-tilting and transverse-shifting mechanism. This case-tilting and transverse-shifting mechanism comprises a vertically-swinging case support or platform 13 mounted, as illustrated on a vertical frame 10 extending upwardly from the tilting platform P, pivotally mounted in the frame 10 of the machine on pivot tip, and swung about said pivot by suitable cam mechanism hereinafter more particularly specified. The tilting platform 13 not only swings or tilts one end of the case upwardly into a position inclined with relation to the bottoms of the bottles but also is provided with means such as the upwardly and outwardly inclined members 13a for engaging the sides of the cases to shift the same transversely and to align the transverse position of the box in relation to the carrier load.

In the upward movement of the case during its tilting movement, the rear walls of the rear honey-comb chambers will first engage the heels of the bottles and upon further downward movement, the case which is somewhat loosely supported will be primarily moved by engagement of the ends or heels of bottles with the walls of the honeycombs. The successive transverse rows of bottles will be consequently inserted successively in the honey-comb chambers.

In our preferred mechanism for engaging and releasing the tops of the bottles (see Figs. 8, 8a, 11 and 17 to 20) we preferably employ a guide and holder member comprising inverted funnels 21, each having its upper portion connected to the relatively-stationary bottle-receiving member and its contracted end communicating with the enlarged bottle receiving apertures so that the inverted funnels extend downwardly beneath such bottle-receiving apertures and upon movement of the transfer-head downwardly over bottles, guide such bottles into the bottle-receiving openings of the relatively-stationary and shiftable plate members carried by said head. After insertion of the bottles, the inverted funnels 21 retain and hold the bottles during the transfer movement of the said head against excessive swinging or tilting movement relatively to the head and when delivery to a honey-comb case is required these funnels maintain the positions of the bottles to enable facile entrance of the same into the honey-combs.

Upon the initial movement of the transfer head downwardly over the tops of a load of bottles, the bottle-tops pass upwardly through the inverted funnels and then through the bottle-receiving openings of the stationary and shiftable members. The shiftable members are adapted in one position to permit the bottles to rise through and above such members but in the engaging position of the transfer head the contracted slotted or forked portions are moved or

shifted to pass beneath the rim beads of the bottles and thus to lock such bottles to the transfer-head. Assuming, therefore, that it is desired to load a case by such transfer-head, twenty-four of these funnel-guarded bottle-receiving openings 15a will be provided in the relatively stationary plate and twenty-four similar bottle-receiving openings 15c in the shiftable plate will in one position register with the openings 15a and when the plate 15b is shifted the communicating contracted bayonet or forked slots will extend above the openings 15a in the stationary member. Upon movement of the head down over the tops of the bottles therefore, the enlarged bottle-receiving apertures in both the stationary and movable or shiftable members will be in alignment and open to receive the tops of the bottles. Upon the carrier reaching its final position over such bottles, actuating mechanism 18 is provided for moving or shifting the said bayonet-slotted portion of the shiftable member longitudinally beneath the rim-beads and the open ends of said forked slot will be closed by a perimetric portion of the relatively stationary bottle-receiving openings so as to lock such tops of the bottles to the head. When this locking is accomplished the carrier is then moved vertically in the arc of a circle to its bottle depositing position whereupon the actuating mechanism will again be operated to shift the shiftable member in the opposite direction, and thus to completely release the tops of the bottles and deposit them on a suitable horizontal support or within the honey-combs of a box as hereinabove described. In this shifting movement, the forked or bayonet slot slides over the relatively stationary opposite edge portion of the stationary opening and positive release is effected, and the bottles pass downwardly by gravity to the depositing platform or honey-comb case.

Our starting support or frame 12 (see Figs. 5, 5a and 5b) has mounted thereon a pair of outwardly-extending angle-bars 12x having their horizontal members facing each other and arranged to provide stationary ways, and our preferred form of spreading device or "article spreader" is mounted on these ways with anti-friction rollers 12y therebetween and comprises a plurality of sectional slats 12' slidably mounted at their opposite ends on said stationary ways of the starting support (see Figs. 2, 5, 5b, 7, 8, 12-15) so as to have a limited and controlled sliding movement relatively to said stationary ways to separate a load of articles from the oncoming feed thereof and also a controlled and limited sliding movement relatively to each other in order to spread rows of articles mounted thereon from each other.

The sectional slats 12' as shown are connected to spread-controlling means comprising a spreading frame composed of two longitudinally-extending spread-control members 12c connected together at the inner ends by a transverse member 12g (see Fig. 5b) both transverse and longitudinal members being fixedly-connected to the end slat. The horizontal member is connected intermediate its ends with operating lever-mechanism hereinafter described and the longitudinal members are slotted at spaced intervals to provide in combination with pins 12a on the other slats a slot-and-pin connection therewith, the pins being held in place in the slots by washers 12w. Said two longitudinally extending spread-controlling members of said frame are arranged parallel to the angle-bar ways 12x and

the outer-end slat preferably has a separate slot-and-pin connection at 12z with the horizontal members of the angle-bar ways, so that outer-end slat member will have a short sliding movement relatively to said stationary ways 12x that is limited by the length of the slots in said stationary ways, thus providing when moved by suitable operating mechanism for a limited movement of a row of articles or bottles mounted thereon away from the incoming feed rows of articles or bottles, as aforesaid. The other slat members will similarly be movable along said ways relatively to said outer end member and will have their respective movements limited and controlled by the slots in parallel spread-controlling members, so as to spread rows of articles or bottles mounted thereon relatively to each other.

In the embodiment shown, there are six slats slidably mounted on the angle-bar ways 12x by rollers 12y. The slat at the inner end nearest the shaft 17 is as aforesaid fixedly fastened to the ends of the spread-control members 12c and thus forms a slat member that cross connects at one end the spread-control members 12c, and is slidably mounted with the other slats on the angle-bar ways 12x by a pair of the rollers 12y. The slidable slat at the opposite or outer end of the support is also slidably connected to the spread-control members 12c, by straps or yokes 12a' spanning said spread-control members 12c. An article-spreading frame is thus produced that has, as aforesaid, a limited and controlled sliding movement relatively to the stationary ways 12x, and the slat members of which also have movements relatively to each other controlled and limited by their slot-and-pin connections with the spread-control members 12c. In order to assure the movement of each of the slats from its adjacent slat and to cause them to move a controlled distance relatively to such adjacent slat and thus to procure proper spreading of the slats and bottles mounted thereon, the controlled movements between the several slats and the spread-control members are progressively lengthened by progressively lengthening the slots of the slot-and-pin connections, thus permitting spreading and spacing of the slats from each other in open position and permitting the closing up of the spaces between slats to permit receipt of a new load of bottles.

It is desirable to provide separate movements at different rates of speed for spreading the slats and for closing the same. Our preferred means for this purpose (see Figs. 12 to 15) comprise the fastening to the cross member 12g, of a longitudinal lever 12h and the engagement and movement by said longitudinal lever of said cross member and said longitudinal members and end slat by suitable mechanism. A swinging crank-lever 12i (Fig. 15) pivoted at 12h' on support 12 is employed to move said longitudinal lever 12h. This pivoted crank is in turn moved by engagement with a fork 12l at the upper end of a vertical lever 12m which is pivoted (see Fig. 13) intermediate its ends at 12m' on the skeleton frame of the machine and has its lower end engaged by an eccentrically mounted pin or stud 12n on a cam-wheel 12o mounted on the reduction gearing shaft RGS to produce a relatively slow opening or spreading movement. To produce the necessary faster closing movement of the slats, I provide (see Fig. 13) a closing lever 12p pivoted at 12q (see Fig. 13) on the machine operated by eccentric stud 12r on the cam wheel 12o and adapted to engage the upright or vertical lever 12m at 75

12p' intermediate its ends and to move the same at a relatively faster rate of speed to closing position. As shown, this differential speed is accomplished by providing separate studs on the cam-wheel with different inclinations on the ends of the operating levers, the shortening of the relative lengths above the pivots of the closing lever, and the engagement by this relatively short lever of the opening lever intermediate its pivot and the fork. The movements of the cams, studs and levers are timed with each other and all are synchronized with the movement of the transfer head so that the bottles will be properly spread when the transfer head reaches its starting position and will then be immediately closed to permit receiving a new load while the said transfer head is having its transfer movement.

It is desirable, so soon as the bottles are received on the spreader to stop the feed of the additional bottles from the feed line and for this purpose I provide a rack 24 including a series of pins 24x (see Figs. 1a, 1b, 1c, 12 and 13) movable upwardly from beneath the starting support to intersect the longitudinal feed channels and into the path of the bottles being fed to the machine. These pins are mounted on a vertically movable cross-member 24' which is in turn mounted on a long vertical lever 24a pivotally connected to a shorter horizontal lever 24b pivoted at 24p to a fixed bracket member 24d and having a cam connection with a cam-wheel 24c on the shaft RGS of reduction gearing.

It is also desirable to lock the spreader after the same is moved to bottle-receiving closed position and for this purpose (see Figs. 1b and 12) I provide on the vertical lever a hook 24e adapted to engage a pin 24f on a downwardly-extending rod 24g on the frame of the spreader. The locking of the spreader and the stopping of the bottles are thus accomplished by the same lever mechanism.

Our preferred form of mechanism for moving the case-support to align the case transversely and to tilt the case longitudinally as hereinabove described, comprises (see Figs. 2, 4, 4a) the mounting of the upright frame members 13, 13' on a horizontal rectangular tilting frame P pivoted near its ends on a horizontal pivot. One side member of the frame P extends rearwardly of the pivot shaft tp and a diagonal member p' connects opposite side members and is pivoted intermediate its ends on said pivot shaft tp and the frame P is tilted by operating lever-mechanism connected therewith at the junction of the diagonal member with said rearwardly-extended side member. Said frame is thus tilted, as shown, by the pivotal engagement at p2 (as shown in Figs. 1, 4 and 5) of one end of a vertically-disposed operating lever P2 pivotally connected at 60 its other end to a horizontal lever p3 engaged intermediate its ends by an eccentrically positioned studs on the same cam-wheel employed for actuating the opening and closing movement of the bottle-spreader. The eccentric stud lowers the horizontal lever P3 which in turn depresses the vertical lever P2 which pulls down the rear end of the frame P and swings the forward end upwardly to tilt the frame P on its pivot tp and to cause the same to return to a horizontal position. The elevated case-supporting members 13, 13' carry at the upper end thereof the laterally extending wedge members 13a which, when a box is mounted on the supporting members will, upon upward tilting of said frame, cause a shifting movement of the box transversely so as to prop-

erly position the same. This is accomplished simultaneously with the tilting of the box longitudinally which as aforesaid causes the end partition to act as guides and thus insures movement of the bottoms of the bottles into the cells or honey-combs of the case or box.

The actuating mechanism 18 for moving the shiftable member of the transfer head engages a contact arm 15x fixedly connected to and extending beyond opposite ends of the shiftable member 15b so as to permit shifting in opposite directions to engage the tops of the bottles and to retain the same on said transfer head during its movement and also to release such tops at one limit of its movement. As shown, the actuating mechanism preferably employed comprises a head 18' and duplicate wedge members 18a having a vertical movement. This pair of wedge members 18a are adapted on vertical movement to engage and to be spread apart by the oscillating shaft 17. Said wedge-members 18a are held together (see Figs. 7, 9 and 10) by a spring 18b and upon vertical movement thereof spread out horizontally to engage the contact arm extensions 15x carried by the shiftable member 15b of the transfer head so as to lock and release said shiftable member 15b on alternate movements of the actuating mechanism 18. The lever mechanism for moving the wedge members vertically comprises a vertical lever 18e guided in guide plates 18c, 18d and connected at its upper end to the actuating head 18' and pivoted at its lower end to one end of a horizontal lever 18e', the other end of which is pivoted on a horizontally fixed pivot rod 18k fast on the frame of the machine. Said horizontal lever 18e' carries a track 18f intermediate its end and this track is engaged by an eccentric stud 18g on the wheel of the circular plate 18h. Upon rotation of the wheel 18h, the stud 18g moves the horizontal lever 18e' about its pivot and raises the vertical lever which in turn moves the operating spreading wedges 18a into engagement with the said oscillating shaft to spread the same horizontally against the action of the spring 18b which tends to hold the said wedges 18a together. On alternative movements, therefore, the wedges 18a which are jointly pivoted at the lower ends to the head 18' at the upper end of the vertical lever 18e are moved or spread horizontally to engage the opposite ends of contact member 15x of the transfer head. The guide plates 18c and 18d cause accurate movements of the wedge members into position to be spread by the shaft 17 and this movement is, as aforesaid, synchronized with the back and forth movements of said transfer head.

In Figs. 1, 2, 3, 6 and 7, I have shown the transfer head 15 mounted on a frame 30 and provided with sliding sleeve members 30a mounted on rods 30b connected to the operating or swinging mechanism intermediate the ends of a cross-rod 30c which is pivoted at its opposite ends on the articulating levers 19. The transfer head is thus mounted by means of the telescoping members 30a and 30b. Besides acting as a safety unit to prevent any crushing of the bottles during a transferring movement thereof, this telescoping arrangement between the transfer head and the main oscillating arms, takes up any variations in the thicknesses of the bottoms of the bottle and of the cases and enables facile operation of the adjacent parts without any breaking stresses or the like.

Our preferred mechanism for oscillating the

shaft 17 to move the transfer head comprises a gear 31 mounted on said shaft and meshing with a larger gear 32 independently mounted on shaft 32' and oscillated by arms 33 fixed thereto at one end and having their other ends pivoted to a vertical transmission rod 34 which is in turn pivoted to a crank arm 35 which is mounted on the gear reduction shaft, GRS.

The operation of the machine and its various parts have been fully described hereinabove and will be clear from the foregoing description.

In Fig. 16 we have shown an embodiment of our invention, employed for removing bottles from a box or case and depositing them on a conveyor belt which may be used to transfer the bottles to any suitable position in the plant. In this embodiment, the transfer head 15 is lowered over a box or case 14 of bottles supported on the starting-support channel bars 12 and 12x from which the bottle-spreading platform has been removed. The bottles in a honey-comb case are spread and our transfer head will engage the same in the manner hereinabove described and will deposit the same on a belt 42 mounted on the vertical flanges of channel-bars 43 by means of rollers 44. In other respects, the construction is similar to that hereinabove shown and described.

It is desirable to counterweight the load of bottles during a transfer or swinging movement of the transfer head and for this purpose, I provide on the oscillator shaft 17 a gear 40 and connect this gear by sprocket chain 39 with a gear 38 mounted on stud shaft 40 on the frame of the machine and fixedly attach to said gear 38 a crank-arm 37 having at its end a counterweight 36, which will oscillate in the opposite direction on each movement of a load.

Having described our invention, we claim:

1. A machine for transferring bottles and like articles embodying, in combination, a starting support for articles to be handled, article-aggregating means for positioning a load of articles on said starting support in transverse rows, a tilting member oscillative vertically having mounted thereon a receptacle having transverse wall members and movable from an initial, substantially horizontal position into an inclined position tilted at an angle to the horizontal and back again, a transfer head, article-engaging means on said transfer head adapted to engage the top portions of said rows of articles to cause the bottom portions to project downwardly below said head in spaced rows, power means for alternately moving said transfer head in a vertically arcuate path about a horizontal axis from a starting position in substantial parallelism and registration with said starting support to a delivery position in substantial registration with said receptacle-tilting member, means for tilting said oscillative receptacle-tilting member in timed relationship to the arcuate movement of said transfer head to cause a transverse wall member of the receptacle in such tilted position of the tilting member to contact the bottoms of the articles in a row of articles to facilitate movement of the articles into said receptacle, and means for moving the article-engaging means on the transfer head to release engagement thereof with the tops of the articles to load the bottles into said receptacle.

2. A machine as claimed in claim 1 in which the article-aggregating means positions a series of rows on the starting support, the movement of the transfer head causes the bottoms of the rows of articles to move in a series of arcuate paths,

and the tilting member has mounted thereon a receptacle with honeycomb compartments, and the movement of said tilting member is timed with the movement of said transfer head to cause initial contact of one of said transverse wall members with the bottoms of a row of articles and in the downward movement thereof to cause other transverse wall members to contact successively with the bottoms of the articles in other rows.

3. A machine for transferring bottles and like articles embodying in combination, a starting support for articles to be handled, article-aggregating means for positioning a load of articles on said starting support in transverse rows, a tilting member oscillative vertically having mounted thereon a receptacle having transverse wall-members and movable from an initial, substantially horizontal position into an inclined position tilted at an angle to the horizontal and back again, a transfer head, article-engaging means on said transfer head adapted to engage the top portions of said rows of articles to cause the bottom portions to project downwardly below said head in spaced rows, power means for alternately moving said transfer head in a vertically arcuate path about a horizontal axis from a starting position in substantial parallelism and registration with said starting support to a delivery position in substantial registration with said receptacle-tilting member, means for tilting said oscillative receptacle-tilting member in timed relationship to the arcuate movement of said transfer head to cause a transverse wall-member of the receptacle in such tilted position of the tilting member to contact the bottoms of the articles in a row of articles to facilitate movement of the articles into said receptacle, means for independently moving the receptacle on said receptacle-tilting member to accurately position said receptacle in relation thereto and to the bottoms of the articles in the transfer head, and means for moving the article-engaging means on the transfer head to release engagement thereof with the tops of the articles to load the articles into said receptacle.

4. A machine for transferring bottles and like articles embodying, in combination, a starting support for articles to be handled, article-aggregating means for positioning a load of articles on said starting support in rows, a tilting member oscillative vertically having a partitioned receptacle mounted thereon and movable from an initial, substantially horizontal position into a position tilted at an angle to the horizontal and back again, a transfer head, an alternately shiftable member on said head having article-engaging and disengaging means and movable in one direction to engage with the tops of a load of articles on said starting support to cause the bottoms of the articles to project downwardly and movable in the opposite direction to disengage said articles over said tilting member, power means for alternately moving said transfer head in said vertically arcuate path to positions over said starting support and tilting member, mechanically movable actuating means synchronized with said power-driven head-moving means for shifting said shiftable member in one direction at said

starting position to automatically engage a load of articles and for shifting said shiftable member in the opposite direction at said delivery position to automatically release said articles, and means for tilting said oscillative receptacle-tilting member in timed relationship to the arcuate movement of said transfer head to cause a partition of the receptacle in such tilted position of the tilting member to contact the bottoms of the articles in a row of articles to facilitate movement of the articles into said receptacle.

5. A transfer machine for bottles and like articles embodying, in combination, a skeleton frame, a starting support for articles to be handled, means for aggregating a load of articles on said starting support in a series of transverse rows, a delivery support comprising a receptacle-tilting member having mounted thereon a receptacle provided with a series of transverse partitions and oscillative vertically to move the receptacle mounted thereon from an initial substantially horizontal position into a position tilted at an angle to the horizontal position and back again, an oscillating power shaft disposed between said starting and delivery supports, a transfer head mounted on said oscillating shaft, power driven means for oscillating said power shaft to move said transfer head in an arcuate path from a starting position in substantial parallelism with said starting support to a delivery position in substantial parallelism over said delivery support, means on said transfer head adapted to engage the top portions of a load of articles and to cause the bottom portions to project downwardly below said head and said transverse rows of articles to move in a series of arcuate paths, means for moving said receptacle-tilting member in timed relationship to the arcuate movement of said head into the path of the bottoms of the said rows of articles to cause each of the transverse partitions of the receptacle successively to engage a row of articles in the transfer head to facilitate the movement of such articles into the receptacle, and means for automatically releasing said top portions of the load of articles in the delivery position of said head.
